UNITED STATES PATENT OFFICE.

ORANGE O. OZIAS, OF DAYTON, OHIO.

DESIGN FOR A PRICE-INDICATING CHART.

SPECIFICATION forming part of Design No. 29,095, dated July 26, 1898.

Application filed June 20, 1898. Serial No. 684,007. Term of patent 31 years.

To all whom it may concern:

Be it known that I, ORANGE O. OZIAS, a citizen of the United States, residing at Dayton, in the county of Montgomery and State of Ohio, have invented and produced a new and original Design for a Price-Indicating Chart, of which the following is a specification, reference being had to the accompanying drawings, forming part thereof.

10 Figure 1 is a side elevation of a price-indicating chart, showing my design; and Fig. 2 is an end elevation of the same.

The leading or material feature of my design consists of a rectangular base 10, having a standard 11 rising from each of the opposite ends of said base, and a flat member 12, intermediate and secured to the upper

ends of said standards and extending at an angle with reference to said base. Upon said member 12 are arranged the longitudinal space-lines 13 and 14, the transverse spaces 15 and 16, and a longitudinal space 17 across said transverse spaces 16.

What I claim is—

The design for a price-indicating chart, substantially as herein shown and described.

In witness whereof I have hereunto set my hand, at Dayton, Ohio, this 14th day of June, A. D. 1898.

ORANGE O. OZIAS.
